UNITED STATES PATENT OFFICE.

HORACE N. HATCH, OF BOSTON, MASSACHUSETTS.

STOVE.

SPECIFICATION forming part of Letters Patent No. 377,454, dated February 7, 1888.

Application filed March 18, 1886. Serial No. 195,658. (No model.)

To all whom it may concern:

Be it known that I, HORACE N. HATCH, of Boston, in the county of Suffolk and State of Massachusetts, have invented a new and useful Improvement in Attachments for Stoves, of which the following is a specification.

My invention relates to stoves, and more particularly to an attachment thereto for retaining or holding down upon them pots, kettles, &c., when they are used at sea and likely to throw off the receptacles in which the cooking is done. The same consists in certain new and improved arrangements of devices for accomplishing this purpose, substantially as hereinafter described and claimed.

In the drawings, Figure 1 is a side view of a stove provided with my improved attachments, as above mentioned. Fig. 2 is an end view of same. Fig. 3 is a top view. Figs. 4 and 5 are detail views of the universal-joint connection used with my device.

S is the stove, which on board a vessel is customarily fastened to the floor. It has around it the usual rail, s, supported upon 25 posts s' on top of the stove, and serving to keep the vessels used for cooking from sliding off. When, however, the vessel gives a lurch beyond a certain angle, these cooking-vessels are frequently thrown against the rail s, which 30 then only serves to capsize them.

My improvement is designed to obviate this difficulty. To accomplish this I cause to rest upon the floor on each side of the stove upright rods a a, which I carry past the rail s on 35 each side and attach to the rail by sleeves s' and set-screws s', the rods a sliding easily through the sleeves s' and being secured by the set-screws s'. The rods s are attached to the top of the stove, so as to give a firm support 40 to the rods a a; but they may be set into the stove-top, so as to be removable, and in that event I have provided additional sleeves, s', having short studs projecting from them a sufficient distance to reach under the stove-body, 45 and provided with set-screws s'. By mounting these upon the vertical rods a, as shown in Fig. 1, and setting up their set-screws, they may be made to serve to hold the feet a' of the rods a firmly upon the floor, and also to hold 50 the rods s in place on top of the stove. The lower ends of rods a are provided with foot-pieces a', bearing upon the floor, and the sleeves

s' are double—that is, they consist of a sleeve fitting to the rods a a and a right-angled sleeve fitting to the rods s s and sliding thereon, as is 55 clearly shown in the drawings. Around from the upper ends of the rods a a and over the stove they are connected by the horizontal rod a'. The sleeves of the connections s', which fit the rods s s, are capable of sliding thereon 60 horizontally, and thus by bringing the feet a' a' to bear solidly on the floor the set-screws s' s' are made to bind the couplings s' not only upon the upright rods a, but also upon the horizontal rods s, and by loosening these set- 65 screws I am able to slide the rods a and rod a' over any part of the stove desired. This adjustment is of importance in enabling me to slide out of the way the rods a a' upon occasions when they are not required. Mounted 70 upon the rod a' are similar double-sleeve couplings, b, consisting of a vertical sleeve and a horizontal sleeve, and a similar coupling is shown attached to one of the upright rods a. One of the sleeves of this coupling b is made 75 to slide upon the rod a or a', and is secured in any desired position thereon by the set-screw b', while the other sleeve has passed through it and capable of sliding therein the straight portion of a bent arm, c, which reaches downward over the tops or covers of the stove, commonly called "stove-lids." These arms c are 80 bent at right angles at c', and have a portion of them extending some distance in that direction from the portion which slides through the coupling b, and in the case of those mounted upon the horizontal rod a', I have shown them as again bent downward and provided on their lower ends with feet or enlargements c'', which are hollowed out on their lower faces in order 85 to fit upon the rounded top or cover of a kettle or other vessel, as shown in dotted lines in Figs. 1 and 2, and this hollowed place in the enlargement c'' may be large enough to receive the handle of the cover and rest down around 90 it upon the same.

In the case of the arm c, attached to the upright rod a, I have shown a frying-pan, F, held down by it by resting the lower end of it in the center of the pan, and this can be done 95 without materially interfering with the operation of cooking in the latter.

The portion of the coupling b which slides along upon the rod a or a' is also provided

with a set-screw, b^2 , to enable it to be fixed upon that rod in any desired position. Since the rods c are capable of turning in the sleeve-couplings b , as well as sliding through them, the arrangement of the couplings with the other parts constitutes a universal joint which allows the lower ends of the rods c to be brought over any portion of the top of the stove that may be desired, and thus secure a cooking-vessel upon any part of the stove-top by simply loosening and tightening the set-screws $b' b^2$.

The capability of sliding the rods $a a^2$ across to any part of the stove and securing them there, combined with the capability of adjustment of the rods c by sliding upon the rods $a a^2$, and by sliding and turning in their couplings b , enables the several adjustments to be made so as not to interfere with the use of other parts of the stove-top than those they overhang for large vessels which do not need to be held down—as, for instance, boilers, &c.—and it also enables me to immediately remove and swing out of the way all these several attachments—viz., rods $a a^2$, couplings b , and rods c —without disconnecting them from each other or disturbing their capacity for immediate adjustment and use with great rapidity.

30 What I claim as new and of my invention is—

1. The combination of the stove provided

with horizontal rods s , the rods $a a^2$, the couplings s^2 , provided with set-screws s^3 , and a brace or rod mounted on rods $a a^2$, and projected downward over the stove, substantially as described. 35

2. The combination of the rod a , the coupling b , provided with set-screws $b' b^2$, and the bent rod or arm c , capable of sliding and 40 turning therein and therewith, substantially as described.

3. The combination of the stove S , the horizontal rod s , provided with the sliding couplings s^2 and set-screws s^3 , the vertical rod a , 45 the coupling b , provided with set-screws $b' b^2$, and the bent rod or arm c , capable of turning and sliding therein, substantially as described.

4. The combination of the horizontal rod a^2 , the coupling b , provided with set-screws $b' b^2$, 50 the sliding and turning bent arm or rod c , provided with the hollowed-out enlargement c^2 at its lower end, and the stove S , substantially as described.

5. The combination of the stove S , the vertical rods $a a$, and horizontal rod a^2 , made adjustable transversely of the stove, the couplings b , provided with set-screws $b' b^2$, and the swinging and sliding arms or rods c , substantially as described. 55 60

HORACE N. HATCH.
